Robert J. Armour, Inventor
By his Attorney A. M. Pierce.

UNITED STATES PATENT OFFICE.

ROBERT J. ARMOUR, OF NEWARK, NEW JERSEY, ASSIGNOR TO THE RAIL
ROAD SIGNAL LAMP AND LANTERN COMPANY, OF NEW YORK, N. Y.

DESIGN FOR A LAMP OR LANTERN BODY.

SPECIFICATION forming part of Design No. 27,898, dated November 23, 1897.

Application filed March 2, 1897. Serial No. 625,802. Term of patent 14 years.

To all whom it may concern:

Be it known that I, ROBERT J. ARMOUR, a citizen of the United States, residing in Newark, county of Essex, and State of New Jersey, have invented and produced a new and original Design for Lamp or Lantern Bodies, of which the following is a specification.

In the accompanying drawings, forming a part hereof, Figure 1 is a side elevation, and Fig. 2 a plan view, of a lamp-body, showing my design, these two views being deemed necessary to fully illustrate my design.

Similar numerals of reference, wherever they occur, indicate corresponding parts in both figures.

The leading characteristic features of my design reside in the shape or configuration of the unitary article made the subject-matter of the illustration, of a lamp or lantern body

substantially spherical in shape, having a central horizontal circumferential flange and flanges or rings projecting from said body at right angles to said horizontal flange.

11 are the two portions of the body, substantially identical in form, each being hemispherical in contour and provided with projecting parts 3 and 4 and flanged parts 5, thus presenting to the eye the combined effect of a sphere, having rings projecting therefrom.

What I claim as new, and desire to secure by Letters Patent, is—

The design for a lamp or lantern body herein shown and described.

ROBERT J. ARMOUR.
